UNITED STATES PATENT OFFICE.

HARRY ALLAN, OF TORONTO, ONTARIO, CANADA.

ROTARY TOOTH-BRUSH.

1,133,907.

Specification of Letters Patent. Patented Mar. 30, 1915.

Application filed July 29, 1914. Serial No. 853,915.

To all whom it may concern:

Be it known that I, HARRY ALLAN, a subject of the King of Great Britain, residing at Toronto, in the Province of Ontario and 5 Dominion of Canada, have invented new and useful Improvements in Rotary Tooth-Brushes, of which the following is a specification.

This invention relates to rotary tooth brushes, and its primary object is to provide a rotary tooth brush embodying a water motor of novel construction whereby the brush may be driven from any ordinary water tap or faucet.

10 A further object of the invention is to provide a novel construction of motor casing, detachable brush, and an adjustable brush guard, allowing brushes to be changed as desired and securing an efficient guarding 20 action whereby injury to the lips from the brush is prevented.

The invention consists of the features of construction, combination and arrangement of parts herein fully described and claimed, 25 reference being had to the accompanying drawing in which:—

Figure 1 is a perspective view showing the device applied to a faucet for use. Fig. 2 is a perspective view of the casing, brush 30 and guard. Figs. 3 and 4 are sections on the lines 3—3 and 4—4 of Fig. 2. Fig. 5 is a sectional view through the motor casing. Fig. 6 is a view of the motor wheel.

In carrying my invention into practice, I 35 provide a disk shaped motor casing 1 comprising a body 2 and a lid or cover 3, said lid or cover being threaded or otherwise detachably engaged with the body. At points in its periphery the casing body is provided 40 with a tangentially disposed inlet nozzle 4 and a radially disposed outlet or discharge nozzle 5, which nozzles are adapted to receive the ends of water supply and discharge pipes or tubes 6 and 7, made of rubber or other suitable material. The free end 45 of the hose or tube 6 is preferably flared to engage a water tap or faucet 8, and is provided with a chain fastening 9, or other equivalent fastening, for holding it in position thereon. In practice, the hose 6 may be applied to one of the water taps above a lavatory basin, and the hose 7 arranged to discharge so that the water therefrom will flow to the basin outlet.

50 The side wall of the body 2 opposite the cover 3 is formed with a circular boss 10

forming a water flow channel 11 with which the nozzles 4 and 5 communicate, said boss having its periphery concentric with the inner periphery of the casing body and being 60 provided with a bearing opening 12. Arranged to revolve within the casing is a motor wheel comprising a hub or disk 13 disposed at one side of its diametrical center and having an annular series of radial 65 blades 14 projecting laterally therefrom. The disk 13 turns in contact with the inner face of the boss 10, which is of less depth and width than the casing, the disk being of such thickness as to fit between the said face 70 of the boss and the cover plate 3, whereby it is guided for motion in a true path. The blades 14 project laterally beyond one side of the disk so that their inner ends ride in contact with the periphery of the boss, while 75 their outer ends ride in contact with the inner periphery of the casing. A motor wheel of simple construction is thus provided which is designed to prevent leakage and to be efficiently propelled by the motive fluid 80 without the necessity of employing complex packing or guiding means. It will be understood, of course, that the water entering through the inlet nozzle strikes the blades of the motor wheel and revolves the same 85 and then discharges through the outlet nozzle.

The disk or hub of the motor wheel is fixed to one end of a shaft 15 which is journaled in the bearing opening 12 and thence 90 extends outward from the motor casing. The outer end of this shaft carries a brush body or head 17, which may be of any suitable construction. As shown in the present instance the brush body is circular and provided with bristles around the same, and said body has a socketed shank 18 engaging the outer end of the shaft and detachably secured thereto by a set screw 19 or other suitable fastening means. By this construction brushes of different kinds may be applied to the shaft for use, and a new brush may be readily substituted for an old one. The shaft 15 revolves within a partially circular guard 20 having at its outer end a 95 spoon-shaped enlargement 21 forming a guard cap within which the brush revolves and which partially receives said brush. The opposite or inner end of this guard member is formed with a right angularly 100 bent bracket arm 21 formed with a slot 22 receiving a set screw 23, whereby it is de-

2

tachably secured to the casing body, the construction also being such that the guard may be adjusted toward and from the shaft and brush, so that the guard may be moved away from the brush to allow the brush in use to be removed and a new one substituted therefor, and then arranged and secured in applied position. The function of the guard is to prevent the lips of the user from being injured by contact with the brush, as will be readily understood.

The mode of application of the device to a faucet or other source of water supply will be readily understood, and it will be seen that when the device is in use the brush will be revolved at a desired rate of speed, thus adapting it to exert a proper cleansing action. The device is properly held or arranged in position for use and the flexibility 15 of the tubes 6 and 7 and comparatively small size of the motor adapt the brush to be handled and properly adjusted in the mouth as occasion requires. The manifold 20 advantages of the invention will be evident 25 from the foregoing description.

I claim:—

1. A rotary brush comprising a casing, a shaft journaled in and extending from said casing, a brush carried by the projecting 30 end of the shaft, means carried by the casing for rotating the shaft and brush, a channeled guard partially inclosing the shaft

and having a spoon-shaped portion partially inclosing the brush, said guard having its channeled portion provided with an angularly bent arm, and means adjustably connecting said arm with the casing for adjusting said guard and its spoon-shaped portion toward and away from the shaft and brush.

2. A rotary brush comprising a flat disk-shaped casing, a shaft journaled in and extending outwardly through one of the flat sides of said casing, a brush carried by the projecting end of the shaft, means carried by the casing for rotating the shaft and brush, a channeled guard partially inclosing the shaft and provided with a spoon-shaped portion partially inclosing the brush, said guard having its channeled portion provided at its inner end with an arm bent at right angles thereto and formed with a longitudinal slot, and a binding screw passing through said slot and entering the adjacent flat side of the casing, whereby the guard and its spoon-shaped portion may be adjusted toward and from the shaft and brush and fixed in adjusted position to the casing.

In testimony whereof I affix my signature in presence of two witnesses.

HARRY ALLAN.
